UNITED STATES PATENT OFFICE.

SIGMUND SPITZER, OF VIENNA, AUSTRIA-HUNGARY.

HULLING-MACHINE.

SPECIFICATION forming part of Letters Patent No. 329,230, dated October 27, 1885.

Application filed July 25, 1885. Serial No. 172,643. (No model.)

To all whom it may concern:

Be it known that I, SIGMUND SPITZER, a subject of the Emperor of Austria, residing at Vienna, Empire of Austria-Hungary, have invented certain new and useful Improvements in Hulling-Machines; and I do hereby declare the following to be a full, clear, and exact description of the invention, such as will enable others skilled in the art to which it appertains to make and use the same.

My invention relates to improvements in hulling-machines for grain; and the object is to construct a machine by which the grain is thoroughly divested of the hulls, bran, &c., in an expeditious and reliable manner; also, to produce a means by which to correctly graduate or regulate the distance between the hulling-stone and the roughened shell or casing.

The invention consists in the construction and arrangement of parts, as will be more fully described hereinafter, and specifically pointed out in the claim, reference being had to the accompanying drawings and the letters of reference marked thereon.

The same letters indicate the same parts in the different figures of the drawings, in which Figure 1 represents a vertical section, partly in elevation, of my hulling-machine. Fig. 2 is a cross-section of the hulling-casing. Fig. 3 is a detail view, on an enlarged scale, of the roughened surface of the hulling-casing.

In the drawings, A represents the hulling-stone, which is roughened on its surface by furrows or otherwise, and is mounted on a vertical shaft, a, in the upper part of the machine. The shaft has suitable journals, and its lower part rests in a suitable step, b. The stone A is surrounded by a casing or shell, C, of sheet-steel, and made in two parts, as seen in Fig. 2, so as to be adjustable. Two screws, c, are attached firmly to the two parts of the casing, and pass through suitable threaded brackets, d, or nuts, and are operated by hand-wheels or cranks, so as to graduate the distance between the stone and the casing as desired. The grain is admitted through the feed-spout e, and after being exposed to the action of the hulling-stone and roughened shell is carried through the spout f into the polishing-machine. In this part is arranged a revolving brush, B, which is secured to the same shaft as the stone. The brush is inclosed in a casing of metal or

wood, and consists of a cylinder with the heads g, and is covered with bristles, card-clothing, or other suitable material. The grain is thoroughly brushed or scoured, so as to relieve it of all dust or fine particles that have not been removed by the hulling-stone and shell. The grain, in descending through the machine, is subjected to the action of an exhaust-fan arranged in the upper part of the spout D. This is connected by a spout, h, with the casing C, and has a branch-spout, i, for the hulls, chaff, &c., while another spout, k, serves to convey the good kernels of grain to a suitable receptacle. The spouts may be provided with valves or ventilators, as desired. The casing C is roughened on its interior surface by sharp points or edges of similar construction to those of a wood-rasp, by which the hulls are better loosened or cut from the kernels, and, being lighter than the kernels of grain, can readily be withdrawn by the action of the suction-fan and separated from the good grain.

The entire machine is arranged in a suitable frame-work, F, and can be thus easily transported from place to place.

The hulling-stone and brush receive their motion through the pulley G, secured to the vertical shaft a. The upper and lower ends of the casing for the hulling-stone and the revolving brush must be made perfectly tight to prevent any dust from escaping.

The grain, having been exposed to the action of the revolving brush B, passes through the outlet-spout l to any suitable receptacle or place. A scale, m, on each side indicates the amount of adjustment of casing C by means of pointers n.

It will be readily understood by those skilled in the art that the hulls, chaff, &c., will be most thoroughly removed by the hulling-machine herein described, while the grain will be made perfectly clean and pure from the scouring action of the brush in its compartment; also, that no parts are liable to get out of order, that the roughened shell of the hulling-stone can be adjusted to a nicety, and that the machine can be produced at very reasonable cost.

The rasp-teeth are struck up out of the sheet-steel casing.

I have shown and described a brushing or

polishing machine, and have referred to and partly shown devices for separating or withdrawing the hulls and light foreign matters from the hulled grain in order to disclose the entire machine used by me and embodying my improvements; but I only claim as new and of my invention the features set forth in the subjoined claim.

Having thus described my invention, what I claim, and desire to secure by Letters Patent, is—

The combination of the movable bisected casing C, set-screws *c c*, having pointers *n*, indicator-scales *m*, and a hulling-stone, substantially as set forth.

In testimony whereof I affix my signature in presence of two witnesses.

SIGMUND SPITZER.
